FUEL BURNER

Eric G. Peterson, Glen Ridge, N. J., assignor to
Peabody Engineering Corporation, New York,
N. Y.

Application March 19, 1938, Serial No. 196,878

5 Claims. (Cl. 158—1.5)

The invention herein disclosed relates to fuel burners generally, but in some respects more particularly to marine type burners.

In naval operations it has become a practice 5 to separate the boilers from the fire room by a gas and water-tight bulkhead forming in effect a wind box about the air registers of the burners. The burner controls of necessity extend through such a bulkhead.

10 Special objects of the present invention are to provide practicable and efficient mounting and control of such burners, particularly to maintain the required gas-tight and water-tight relation of parts at opposite sides of the bulkhead, 15 to allow for such expansion and "weaving" as may naturally occur in such constructions and to prevent such relative movement from affecting or interfering with proper control and use of the burners.

20 Additional objects of the invention are to obtain more thorough and intimate mixing of the air with the fuel, to enable operation with the diffuser positioned within the air register, instead of at the minimum throat diameter rearward 25 of the air register as heretofore and in this way to effect with a given draft loss, combustion of a greater amount of fuel per square inch of throat area. A further object is to enable air supply to a burner to be completely cut off when 30 one of a group of burners firing the furnace is shut down, as practised in marine work.

Further objects and the novel features of construction, combinations and relations of parts by which the purposes of the invention are attained will appear and are definitely set forth in the following specification and illustrated in the accompanying drawings.

The drawings accompanying and forming part of this specification show by way of illustration 40 certain preferred embodiments of the invention and such as are now considered the best modes of applying the underlying principles. Other embodiments of the invention employing the same or equivalent principles may, however, be used and structural changes made as required or desired by those skilled in the art, without departure from the present invention and within the true spirit and broad scope of the patent 45 claims herein.

50 Figure 1 is a broken vertical sectional view of one of the burners.

Figure 2 is a view similar to Figure 1 illustrating a modified form of operating control.

55 Figure 3 is a broken sectional detail showing

portions of the air register as on substantially line 7—7 of Fig. 2.

Figure 4 is a broken and part vertical sectional view of a modified form of burner as constructed for use without the separating bulkhead and 5 with the radial vanes adjustable to operate as a damper and the diffuser equipped with a shroud.

Figure 5 is a broken and part sectional side elevation of a modified form of diffuser with 10 two sets of adjustable air controlling blades.

Figures 6 and 7 are broken sectional views as on lines 10—10 and 11—11 of Figure 5.

Figure 8 is a broken detail of the radial dampers and front ring which pivotally supports the 15 outer ends of said radial dampers.

The naval type burner shown in Figure 1 is designed for installations where a bulkhead 1 covers the furnace front 8. This bulkhead is shown as having an opening 7a of sufficient size 20 for complete removal of the burner therethrough and which opening is normally closed by a removable finish ring 7b.

The air register of the burner is shown as of the general type disclosed in Peabody Patent 25 No. 1,527,214 of February 24, 1925, having curved doors 9 in frustro-conical arrangement pivotally engaged on the spacer sleeve 9a about the connecting bolts 10 between the back plate 10a and the front supporting ring 11.

30 Adjustment of the air doors from closed overlapping condition to a partially or wholly open condition is effected in the illustration from a ring 12 rotatably held on the supporting ring 11 by confining clips 13 and having rearwardly 35 projecting pins 14 engaging in slotted adjusting cams 15 extending from the front ends of the doors.

A bearing is shown at 16 removably bolted at 40 17, Figure 4, on the support ring 11, in which 40 is journaled a short door adjustment shaft 18 carrying at its rearward end a slotted lever arm 19 engaging a pin 20 on the front of the adjusting ring 12. At the front end this shaft is shown 45 as carrying a lever 21 slotted at 22 to receive a crank pin 23 on the rearward end of an operating handle shaft 24 journaled in the finish ring 7b of the bulkhead at 25 and provided with an operating handle 26 on its exposed front end 50 at the front of the bulkhead. The bearing for this operating handle shaft is shown as equipped with a stuffing box 27 and an abutment shoulder 24a is shown on this shaft engageable with the inner end of the bearing to prevent outward 55

movement such as might disengage the crank pin 23 from slotted lever 21.

The mounting of the operating handle in the finish ring of the bulkhead independently of the rest of the burner and the slotted lost motion connection at 23 between this handle and the air register allow for relative movement between bulkhead and burner such as might result from expansion or weaving and prevent such movements from varying or interfering with the desired setting of the air register.

Preferably, the air register is definitely retained in the position of desired adjustment by means such as a notched segment on the operating ring 12 engaging a spring detent mounted on the register support ring 11. This segment may be notched to hold the air doors 9 in the closed, open and partly open positions of adjustment. The spring detent thus constitutes in effect a releasable locking means. If the furnace front 8 and lever 21 supported therefrom move relative to the bulkhead, the operating handle 26 may rotate slightly due to the motion transmitted by pin 23 and shaft 24; however, as handle 26 is free to rotate in bearing 25 no strain is imposed on the linkage of such operating mechanism because of such relative motion.

To increase the turbulence and whirling effect and to augment the supply of air admitted about the periphery of the register, there is provided in the illustration a bladed front cover for the register, indicated as a ring 30 bolted to the register support ring 11 at 31 and having conically disposed frontwardly inclined spaced curved blades 32a designed to impart rotation to an axially entering stream of air in the same sense as the rotation imparted by the peripheral air doors. In some instances these blades may be placed to impart opposite rotation or no rotation at all to the axially entering stream of air.

To shut off or adjust the axial supply of air, there is provided in the present disclosure, Figs. 1 and 2, a series of radially disposed dampers 32 journaled at their outer ends at 33 in the annular ring portion 30 of the bladed front cover and rotatably held at their inner ends in seats 34 in the hub portion 47 of this cover by an overstanding damper hub 35, secured to hub portion 47 by bolts 36.

The inner journaled ends of the dampers 32 are shown as formed with crank extensions 37 engaging in slots 38 in a damper operating cylinder 39 rockably mounted on a support tube 40. This rocking damper operating cylinder is shown as having a lever arm 41 carrying a pin 42 engaged in slot 43 in an arm 44 projecting from the air door adjustment shaft 18. Actually this arm 44 may be and is shown as a reversely extending portion of the slotted lever 21 which provides part of the connection with the hand crank 26.

The splitting of the bearings 34 for the radial dampers 32 between the front cover hub 47 and damper hub 35 enables easy assemblage of the parts by slipping the outer journal ends of the dampers in the bearings 33 and then applying the separable hub portion 35 over the inner journal ends of the dampers.

It will be apparent that adjustment of the air doors by operating handle 26 also will effect adjustment of the dampers controlling the axial flow of air and in the same sense, that is, in the same opening or closing direction. The relation of parts is preferably such that these

dampers will be fully opened or fully closed as the peripheral air doors are fully opened or fully closed. It is contemplated that for some installations the adjustment of the air doors and the dampers may be independent one of the other.

The support tube 40 is shown as secured by an inclined set screw 45 in a deep seat or socket 46 in the front end of the support tube hub 47 joining the inner ends of the fixed or stationary 10 deflector blades 32a.

To provide a sealing connection between the support tube 40 and the finish ring 7b of the bulkhead, an annular corrugated expansion tube 48 is shown about the support tube secured at 15 its rearward end by an adjustable sealing flange 49 to an expansion tube connector 50 on the finish ring and similarly held at its front end by an adjustable sealing flange 51 to the support tube hub 52 fixed at 53 on the front end of the support tube. Gaskets 125 are provided intermediate 49 and 50 and intermediate 51 and the flange portion of hub 52 for properly sealing the flexible bellows or Sylphon 48 at its ends.

Within the air register portion of the burner 25 is a conical diffuser 55 fixedly secured upon a diffuser pipe 54, which pipe is supported in rear bearing 56 and front bearing hub 52. Hub 52 is secured to 40 by a set screw 53. Set screw 53 seats upon a metallic gasket which in turn seats 30 on a spot faced boss so as to obviate leakage at this point.

A stuffing box flange 57 is shown adjustably secured at 58, to the hub member 52 on the front end of the support tube for providing a 35 stuffing box connection between said support tube hub and diffuser pipe 54 protruding therethrough and a set screw is indicated on this stuffing box flange at 59 for securing the diffuser pipe in various positions of in and out adjustment. 40

To confine the diffuser pipe to straight in and out adjustments and prevent rotation of the atomizer which is carried thereby, a guide screw is shown at 60 extending through the support tube and into a longitudinal slot 61 in the top of the 45 diffuser pipe. This screw also is located to serve as an abutment for retaining the damper operating cylinder 39 in engagement with cranks 37 of the damper vanes 32.

The diffuser 55, in Figs. 1 and 2, is shown as 50 of conical form and as radially corrugated, with slots 62 cut through adjoining the peaks or ridges of the corrugations, in line with the surfaces at the inside, as in Fig. 2, and at the proper side of the ridges to effect rotation inside the diffuser in the same sense as the peripherally and axially entering primary and secondary supplies of air. The end portion 56 of hub 47 adjacent the diffuser is shown as formed with an annular cutout 63 to seat the hub portion of 60 the diffuser when the latter is backed out to the outer limit of adjustment.

The design of the diffuser, by the identity of all corrugations is such as to permit with the same casting, cutting the slots 62 for either 65 clockwise or counterclockwise rotation of air, as may be required by the direction of air rotation through air doors 9, dampers 32 and stationary blades 32a.

The radial dampers 32 are shown as closing 70 at their peripheral edges against an annular sealing shoulder 82. They are indicated further as having vane portions 83, extended beyond their pivoting axes 33, and shorter than the body portions of the dampers at 83a, so as to swing in- 75

side and clear the sealing shoulder 82, as the dampers are opened and to lap behind the forward edge of the adjoining damper when the dampers are closed. These radial dampers are thus made capable of effectively closing off the axial flow of air.

Figure 2 illustrates a modification in which the operating handle 26a is carried by a shaft 24a which is journaled in a bearing and stuffing box 21a carried by an annular enlargement or head 84 on the hub 52a on the end of support tube 40. A pinion 85 on the rear end of shaft 24a meshes with a ring gear 86, fixed on the front end of a sleeve 87, rotatable upon the support tube as a bearing, within the expansion tube 48 and connected at the rear by set screws 98 with the damper operating cylinder 39a. A flange 99 closing the back of the annular head 84 enables assembly of pinion 85 with ring gear 86 and serves as a mounting for the sealing flange connection 51 for the front end of expansion tube 48. This construction permits the joint between flange 99 and the ring 51 at the outer end of expansion tube 48, to be maintained if it be found desirable to remove the entire gear assembly and which latter is possible upon release of the bolt fastenings 99a, connecting flanges 84 and 99, and releasing set screws 53 and 59, Fig. 2.

The lever arm 41a projecting from the cylinder 39a in the Figure 2 construction, carries a pin 42a engaging in slot 43a of arm 44a dependent from the air door operating shaft 18.

The operating handle 26a is shown as having a spring pressed detent 88 engageable in notches in a segment 89 mounted on the front end of the support tube hub 52a, which latter is in effect an extension of the bladed front cover 30. A stop 90 is shown adjustably secured at 91 on this segment to limit the throw of crank 26a to the desired maximum opening movement of air doors 9 and dampers 32. The operating handle 26a and all the intermediate train connecting it with dampers 32 and air doors 9 are supported on the furnace plate 8. Consequently, any relative motion between the furnace front and bulkhead 7 will have no effect upon the setting of the air doors, dampers and adjusting handle and these will not be subjected to distorting stress.

Where bulkhead operation is not required, the burner may be constructed as illustrated in Figure 4, with the door operating shaft extended as at 18a and directly carrying the crank arm 101 in which is rotatably mounted the hand wheel 26b. The spindle of this hand wheel is shown as screw-threaded at the back at 102 to carry a clamp plate 103 and set screw which latter, by turning of the hand wheel can be made to grip a fixedly supported indicating and locking quadrant 104 against the back of the crank arm.

The clamp block 103 is loosely held in a non-rotatable relation in a recess 105 in the back of crank arm 101. Upon turning the hand wheel in one direction the clamp plate can be freed of gripping engagement with the quadrant and the crank arm 101 be then swung by the hand wheel in one direction or the other to completely or partially open or close the air doors and dampers and when the desired adjustment is effected, the hand wheel can be rotated in the opposite direction to secure the crank arm in locked engagement with the quadrant, which with suitable indications on the front of the same will then show at a glance the position in which the peripheral air doors and dampers are secured.

In the construction shown in Fig. 4, the dampers 32 are omitted and control of the axial flow of air is accomplished by making the axial flow directing vanes adjustable instead of non-adjustable. These vanes, here designated 32b, are shown as having pivot pins 106, at their inner ends, journaled in bearings 107, in the support tube hub 56, and pivot pins 108, at their outer ends, journaled in the support ring 30a and having cranked portions 109 engaged in slots 110, of the damper operating ring 111, journaled on the front of support ring 30a. This damper operating ring is shown as carrying at the top a pin 112, engaged by slotted lever 44a of the hand crank shaft 18a.

Also in Fig. 4, the diffuser is shown as carrying a shroud sleeve 113, extending in overlapping relation at 114, over the inwardly projecting fixed shroud sleeve 115, carried by the front support ring 30a.

The structure of the diffuser may be further varied. Particularly, provision may be made for variable regulation of air flowing into and through the diffuser cone. Thus as shown in Figs. 5, 6 and 7, the air passages through the diffuser cone may be provided between overlapping blades 116, adjustably held by the bolts 117, between the inner and outer cone rings 118, 119.

Figs. 5 and 6 show how the hub 120 of the diffuser may carry a cylindrical air inlet member having peripheral air inlets provided between the overlapping blades 121, adjustably secured by bolts 122.

It is realized that in some instances, it is desirable to have both conical and circumferentially arranged adjustable air inlet blades in the diffuser and that in other instances, it may be desirable to have only one or the other set of air inlets variable and the remaining set fixed or non-adjustable. Also it is realized that the diffuser may be made either with or without either the circumferential or the conically arranged air inlets. It is possible further, that the shroud may or may not be used with any of these various forms of diffusers.

Operation

The burner structure is supported from the furnace front 8 and the parts which project through the bulkhead are flexibly sealed to that wall so that misalignment, weaving and any relative movements as between furnace and bulkhead will have no injurious effect on the mechanism, operation or adjustment of the burner. The corrugated expansion tube 48 which seals the front end of the support tube 40 and the support tube hub 52 to the finish ring of the bulkhead is sufficiently flexible to allow for such movements and can be both gas-tight and liquid-tight to prevent flow of gas in either direction and to prevent flow of water in case of flooding at either side of the bulkhead. The same sealing effect is accomplished at the control handle 26 or 26a which operates through a stuffing box either in the finish ring of the bulkhead as in the first example, Figure 1, or in the support tube hub as in the second example, Figure 6. In the first instance, the lost motion or pin and slot connections such as designated 22, 23, 42, 43, Figure 1, prevent vibration or shifting of the bulkhead wall from affecting the burner adjustments. In the construction shown in Figure 2, no lost motion is required since there is no relative movement between handle 26a and the parts which it operates. In both examples, the rocking of the operating handle 26 or 26a one way or the other

45

50

55

60

65

70

75

will effect angular rotative movement of the ring 12 for adjusting the air doors 9 in an opening or closing direction and a rocking of the operating cylinder 39 or 39a to turn the damper vanes 32 in a corresponding opening or closing direction.

Thus, the secondary axial supply of air controlled by dampers 32 is controlled simultaneously and if desired proportionately to the primary supply of air admitted by peripheral doors 9. The air doors and dampers are linked together so that the securing of the adjusting ring 12 serves to secure both in the desired position of adjustment. As the area controlled by dampers 32, even when these are in partially closed position can be, and is as illustrated, materially greater than that between the fixed blades 32a, adjustments of dampers 32 by operating handle 26 or 26a within the range of handle movement required to produce the desired variation in the operating position of doors 9, will not restrict to a measurable degree the flow of air through blades 32a. Thus, while flow through doors 9 may be varied, the flow through blades 32a may be substantially constant. The connecting linkage is so proportioned that dampers 32 will close fully when air doors 9 are in the closed overlapping position.

The fixed radially extending and conically disposed blades 32a direct the axial flow of secondary air tangentially and outwardly, imparting a whirling motion in the same sense as that imparted to the main air supply admitted by the peripheral curved set of doors 9.

This provides a greater flow of air to the burner throat and hence greater capacity for a given draft loss than could be obtained with flow through peripheral doors 9 only. Furthermore, the tangential axial flow stabilizes pressure conditions at the front of the register which, due to the vortex action created near a solid front cover with air admitted through peripheral doors 9 only, tends to be somewhat unstable under the especially severe operating conditions of naval boiler firing.

Part of the whirling air from blades 32a being directed outwardly, mingles smoothly with the flow of air entering by way of doors 9, passes over the periphery of diffuser 55 and is directed into the diverging oil spray from tip 80 by conical back plate 10a. Another portion of this whirling flow of air is directed towards the conical front of diffuser 55 and passes through radial slots 62 in the sides of the corrugations and across the inclined faces at the inside of the diffuser, in the same whirling sense breaking up and mingling with the spray issuing from atomizer tip 80.

The back plate 10a of the resister, having its front conical face perpendicular to the peripheral door centers 10, instead of being curved or in two joined conical sections as in customary practice and making an acute angle with the burner throat 100, directs the rotating air toward the oil spray in such a way as to effect maximum mixing effect without undue flame spread in the furnace. The diffuser being located wholly within the conical air register has a minimum of choking effect on the burner orifice.

If conditions require the shutting-down of any burner of a group firing one furnace, this can be effected quickly by shut-off of fuel and turning of the operating handle 26 or 26a to close the air doors 9 and dampers 32. In this operation the air register is completely closed against air flow through it into the furnace and as the

atomizer is withdrawn, the diffuser pipe is automatically closed against gas or water flow in either direction and maintained so by the self-closing check valves.

It will be noted that possible points of leakage between boiler room and fire room and vice versa and the sealing of same are: between bulkhead 1 and finish ring 1b, sealed by a bolted gasket joint; bearing 25 and finish ring 1b, sealed by a welded or similar connection; shaft 24 and bearing 25 sealed by stuffing box 27; finish ring 1b and expansion tube connector 50, sealed by a bolted gasket joint; connector 50 and expansion tube 48, sealed by a flanged gasket joint at 49; expansion tube 48 and support tube hub 52, sealed by a flanged gasket joint at 51; support tube hub and diffuser pipe 54 sealed by a stuffing box at 57; diffuser pipe and coupling case 64, sealed by a pipe thread or similar connection; coupling casing, sealed by check valves 67, 68. Thus, with the atomizer removed, no flow is possible from one compartment to the other.

With the atomizer inserted, the seal provided by check valves 67, 68 is broken. However, the securing of the atomizer in firing position automatically seals it in the outer end of the coupling and check valve casing at 18.

While illustrated in the form of a liquid fuel burner, the invention is adapted also to burners for gaseous and solid fuels, alone or in combination with liquid fuel. It is contemplated that the structure may be altered and designed to meet special requirements. For example, as in Fig. 8, the dampers 32 may be omitted and the bladed front cover be modified by mounting the blades 32a for adjustment so that they will serve the function of dampers as well as deflectors. For some special purposes these blades may be arranged for rotation of the secondary air opposite to that of the primary air admitted by the doors or the blades be disposed in a plane perpendicular to the axis or in a reversely inclined cone from that shown.

Individual units of the burner, such as the automatic check valve coupling may be used with atomizers and air registers of types different from those illustrated and similarly, the air register comprising the frusto-conical and rotary axial air admission control may be used without the special structure required for avoiding leakage in bulkhead firing.

Without the bulkhead the burner can be simpler and more compact, as shown in Figure 4, with the parts close-coupled and the hand control crank directly on the forward end of the air door operating shaft. The hand wheel 26b in this form of the invention provides a means for securing and locking the air doors and dampers in any one of an infinite number of adjustments.

In all forms of the invention the parts are readily assembled and are readily accessible for inspection, removal or repair. Upon taking off the finish ring 1b in the bulkhead type burner, Figures 1 and 2, the entire air register is exposed and, if desired, may be removed as a unit in its assembled condition through the bulkhead opening 1a.

The adjustable telescopic shroud Fig. 4 may be substantially cylindrical as shown, or otherwise shaped to maintain desired separation of the peripherally and axially entering whirling streams of air.

The diffuser structures illustrated in Figs. 5 and 6 with circumferential slots and conically

arranged slots for entry of air, particularly in the adjustable blade forms, enable desired control of air flow to the inside of the cone.

The telescopic relation between the cylindrical shroud member 113, Fig. 4, carried by the perimeter of the diffuser or flame cone and extending rearwardly from the furnace opening and the second fixedly supported cylindrical member 115, enables any desired axial adjustments of the flame cone to be made without impairing the shielding effect of the shroud. In all such adjustments, this shield prevents rearwardly directed air streams flowing toward the furnace opening from striking the outer surface of the cone and deflecting therefrom into the path of air streams entering through the register doors.

By forming the slots 43 and 43a, Figs. 1, 2 and 4 in different cam shapes, various desired proportional operations of the air doors 9 and shutters 32 can be effected. The flexible bellows seal 48, Figs. 1 and 2, may be of helical design and have screw engagement at opposite ends in the retainer flanges 50 and 51. In practice, the bellows is usually screwed entirely through such flanges to expose the ends of the bellows to suitable gaskets 125, interposed between end flanges 50, 51 and the securing flanges 49 and 126 Fig. 1 and 49 and 99 Fig. 2, which are opposed thereto. Thus these gaskets directly engage flange portions at the ends of the bellows and the portions of the bellows which are screwed in the end flanges take all mechanical strains, thereby relieving the seal portions of strain.

The invention may be modified and changed to meet particular requirements and the special features of the invention may, in some cases, be employed alone or used in different combinations.

What is claimed is:

1. An air register having a peripheral set of air doors and a bladed front cover for admitting an axial flow of air, said bladed front cover having a central hub portion, a support tube carried by and projecting from said hub portion of said bladed front cover, a cylinder journaled to rock on said support tube, dampers on said bladed front cover connected for operation by said rocking cylinder, an air door operating ring rotatably associated with said bladed front cover and operating linkage between said door operating ring and said damper operating cylinder.

2. An air register having a peripheral set of air doors and a bladed front cover for admitting an axial flow of air, said bladed front cover having a central hub portion, a support tube carried by and projecting from said hub portion of said bladed front cover, radially disposed dampers pivoted at their outer ends in said bladed front cover structure and having their inner ends rotatably engaged with said hub portion, a damper hub removably engaged over said inner ends of the radial dampers and means engaged with said dampers for variously adjusting the same. 5

3. An air register of the character disclosed, comprising peripherally arranged air doors, radially disposed air deflecting blades, dampers 15 controlling axial air flow to said radial blades, the flow area by said dampers being materially greater than that by said radial blades, means for effecting adjustment of said peripheral air doors and said dampers and including operating connections between said dampers and peripheral air doors to cause said axial flow to remain substantially constant through the range of operating settings of said peripheral air doors and to effect the closure of said dampers with the closure of 20 25 said peripheral air doors.

4. A burner, comprising in combination, an air register having peripherally disposed adjustable doors to regulate and direct air flow, centrally disposed fuel supply means, blade means for directing supplemental air axially of said register and outwardly with rotary motion, said peripheral doors and blade means cooperating to stabilize air flow in the burner and adjustable damper means for shutting off or permitting air flow 35 to said blade means. 30

5. An air register, having a peripheral set of air doors and a front cover with openings for admitting an axial flow of air, said front cover having a central hub portion, a support tube carried by and projecting from said hub portion, a cylinder journaled to rock on said support tube, said cylinder having slots therein, radially disposed dampers pivotally mounted on said front cover and having cranked inner ends engaged 45 in said slots in said rocking cylinder, an air door operating ring rotatably mounted on said front cover, and operating means for said rocking cylinder and ring. 40

ERIC G. PETERSON. 50
